UNITED STATES PATENT OFFICE.

CHARLES H. SIMPSON, OF LOUISVILLE, KENTUCKY.

AUTOMATIC GATE-OPENER.

1,216,740.

Specification of Letters Patent. Patented Feb. 20, 1917.

Application filed July 13, 1916. Serial No. 109,077.

To all whom it may concern:

Be it known that I, CHARLES H. SIMPSON, a citizen of the United States, residing at Louisville, in the county of Jefferson and State of Kentucky, have invented certain new and useful Improvements in Automatic Gate-Openers, of which the following is a specification.

My invention relates to new and useful improvements in gates and more particularly in gate operating mechanisms, the primary object of my invention being the provision of a simple and durable mechanism by means of which a gate may be opened and closed from a distance and, when closed, may be secured against swinging.

A still further object of my invention consists in providing a novel structure of the above described character by means of which the gate may be operated from either side in such a manner as to swing either toward or away from the operator, as preferred.

In carrying out my invention, I mount the gate for swinging movement and provide a spring latch for securing it in closed position. In connection with the gate so mounted I employ a pair of compound operating members or levers, one part of each member being revoluble in the other and operatively connected to the latch so that by turning such part the latch may be released and the other part of each member being mounted for swinging movement and so arranged that upon release of the latch, swinging of such part will cause a swinging of the gate, the gate swinging in one direction or the other dependent upon the direction of swinging of the operating member.

A further object of my invention consists in providing a novel and efficient means for connecting the operating members to the latch and gate including a drag link adapted to be reciprocated by swinging of such members and serving as a housing for latch operating cables.

With these and other objects in view, my invention will be more fully described, illustrated in the accompanying drawings, and then specifically pointed out in the claims which are attached to and form a part of this application.

In the drawings:

Figure 1 is a perspective view of the gate.

and operating mechanism constructed in accordance with my invention;

Fig. 2 is a fragmentary top plan view, showing certain features of the operating mechanism;

Fig. 3 is a fragmentary sectional view taken through the level of the drag link;

Fig. 4 is a vertical sectional view taken through one of the operating members or levers;

Fig. 5 is a fragmentary horizontal sectional view showing the connection of the latch operating cords with the operating members;

Fig. 6 is a fragmentary elevation, showing the latch and keeper for securing the gate in closed position.

Corresponding and like parts are referred to in the following description and indicated in all the views of the drawings by the same reference characters.

In order to insure a clear and accurate understanding of my invention, I have illustrated a gate 10 including a hinged stile 11 and latch stile 12, and a plurality of horizontal spaced rails 13. The rails at one end are mortised into the hinged stile 11 and at their other end are secured between the spaced sections of the latch stile. The gate further includes opposed vertical braces 14 secured to opposite sides of the rails and in spaced relation to the latch stile and opposed diagonal braces 15 secured to opposite sides of the rails and extending from the upper portions of the vertical braces to the lower portion of the hinged stile. This gate is mounted to swing between gate posts 16 and 17, the former constituting the hinge post to support the gate and the latter a keeper post to limit the swinging movement of the gate and to secure it in closed position.

As best shown in Fig. 1 of the drawings, the gate stile 11 projects at its upper end a considerable distance above the upper rail 13 and at a point somewhat above this upper rail is reduced to form a cylindrical portion which seats in the bight portion 18 of a U-shaped strap metal bearing 19, the ends of which are secured against opposite sides of the hinge post 16. The lower end of the stile 11 is provided with a trunnion, shown in dotted lines in Fig. 3 at 20, which seats in a suitable bearing carried by the gate post 16, so that the gate 10 is free for swinging movement about the

post. The post 16 may be provided with a substantially cross shaped platform or pedestal 21 resting upon the ground, under which circumstances the bearing for the trunnion 20 will be formed in one of the arms of the platform and diagonal braces 22 will extend from the other arms to the intermediate portion of the post. In any event, the lower end of the post will be anchored in the ground or otherwise suitably secured and the post will be suitably braced against any tilting movement.

In like manner, the keeper post or latch post 17 may be provided with a base or pedestal 23 from which the braces 24 will extend to the post. If this post 17 is merely anchored in the ground or otherwise mounted, suitable means will be provided for bracing it. Secured to the inner face of the post 17, is a keeper 25 which extends transversely of the inner face of the post and which is provided intermediate its length with a vertically disposed latch receiving notch 26 to receive an intermediate portion of a resilient latch bar 27 secured at its lower end to the outer face of the stile 12, as shown at 28 and with its upper end normally spaced from the stile. The latch link 29 is pivotally connected at one end to the free end of the latch bar 27 and is slidably mounted between the members of the stile 12, the braces of the gate and certain of the rails of the gate. The opposite end of this link is pivotally connected, as shown at 30, to the intermediate portion of a latch lever 31 which is pivoted at its lower end to one of the lower gate rails, as shown at 32, the upper end of the latch lever projecting above the top of the gate and being located preferably at a point near the hinge stile 11.

At either side of the hinge post 16 and spaced any desired distance therefrom, I mount supporting posts 33 which may be provided with any suitable base 34 and which may be braced, as shown at 35. If preferred, however, these posts may be merely set into the ground or otherwise secured in proper position. Although these posts may be located at any desired distance, within reason, from the hinge post of the gate, they are preferably disposed at such a point that when the gate is swung to open position, its stile 12 will engage against one of the posts or its brace to limit its opening. Secured to the forward face of each post is a spacer bracket or block 36 which, as best shown in Fig. 4, carries a pivot pin 37 projecting forwardly and threaded at its free end to engage in the threaded bore formed diametrically of a cylindrical lever 38, the lever being pivoted intermediate its length upon this pin 37. Surrounding each of these levers is a sleeve 39 which is free for partial rotation about the lever, being slotted, as shown at 40, for the passage of the pivot

pin 37. The upper ends of these sleeves terminate somewhat short of the upper ends of the levers 38 and carry peripherally grooved wheels or drums 41, each of which is provided with an eye 42. The sleeves at their lower ends are provided with substantially circular handles 43 in order that they may be readily turned with respect to the shafts 38. This handle also, of course, permits subsequent swinging of both the shaft and its sleeve about their pivot 37, as will be later explained. A tubular drag link 44 has its ends bifurcated for pivotal connection with the upper ends of the levers 38, as best shown at 45 in Fig. 4, and the intermediate portion of this drag link passes through an opening 46 formed in the upper portion of the hinge post 16, resting upon a supporting roller 47 mounted within the opening and forming a support for the link. Cords or cables 48, which may be of fiber or wire, as preferred, are secured at their ends to the eyes 42 and are passed inwardly through slots or openings 49 formed in the link 44 adjacent its free ends, are threaded through the link to points adjacent the hinge post, and are then passed outwardly through slots 50 in the link, about pulleys 51 mounted upon the upper end of the hinge stile 11 of the gate and are secured to the upper end of the latch lever 31. Idler rollers or pulleys 52 are mounted within the link 44 adjacent the slots 49 and 50 and the cords or cables 48 are passed over these rollers or pulleys in order to prevent chafing of the cords through engagement with the walls of the slots and in order to reduce the force necessary to pull the cables through the link to operate the latch.

As will be readily appreciated, turning of either of the sleeves 39 about its supporting lever 38, in either direction, will cause the tightening of that cord 48 attached to such sleeve, which will act through the latch lever 31 to draw the latch bar 27 out of engagement with the keeper 25 and release the gate.

The upper end of the hinge stile 11 of the gate is reduced to form a trunnion 53 to which is fixed a grooved wheel or winding drum 54. The intermediate portion of a cord or cable 55 is wound once about the periphery of this wheel or drum in such a manner that its ends extend past each other, as clearly shown in Fig. 2, these ends being secured to the drag link 44 adjacent the free ends of the link by means of eyes 56 carried by the link. The intermediate portion of the cable at that side of the wheel or drum opposite the point where the cable ends cross is anchored to the wheel or drum to prevent slipping by a staple 57 or other suitable fastening device.

From the foregoing description of my invention, taken in connection with the drawings, the operation of my gate and its actu-

ating mechanism will be readily understood. Assuming that the gate is in closed position and latched, the latch may be released by grasping either of the handles 43 and turning the sleeve to which such handle is attached in either direction, as previously explained. When the gate has thus been released, the entire gate operating member, including the lever 38 and sleeve 39, may 10 be swung in either direction to swing the gate to open position, a swinging of the lower end of either lever, in the direction of the hinge post of the gate, causing a swinging of the free end of the gate toward the lever swung, while a swinging of the lever in the opposite direction will swing the gate away from the gate operating lever being manipulated. It is, therefore, possible with either gate operating 15 lever to swing the gate in either direction. Obviously, assuming the gate to be open, it may be swung to closed position by swinging either gate operating lever in the proper direction. Obviously, as soon as the 20 gate reaches closed position, its latch will automatically engage the keeper to lock the gate unless restrained from such movement by a too firm grasp upon one or the other of the handles.

30 Although I have illustrated and described my invention in all its details of construction, it will of course be understood that I do not wish to be limited to such details but reserve the right to make any changes in the details or arrangement of parts which I find advisable, within the 35 scope of the appended claims.

Having thus described the invention, what is claimed as new is:

40 1. In a gate mechanism, the combination with a swingingly mounted gate, a latch for securing the gate in closed position, and a swingingly mounted latch lever for releasing the latch, of a hand lever pivoted 45 intermediate its length, operative connection between the hand lever and gate whereby swinging of the hand lever will swing the gate if the latch is released, a sleeve enclosing the lever and free to turn upon it, and operative connection between the sleeve 50 and latch lever whereby turning of the sleeve will actuate the latch lever to release the latch.

2. A gate construction including gate 55 posts, a gate swingingly mounted between the posts and including a hinge stile, a latch carried by the gate, a keeper carried by one of the posts and engageable by the latch, a latch lever swingingly mounted upon the gate and operatively connected to the latch, a drum having fixed connection with the hinge stile whereby turning of the

drum will turn the gate, levers swingingly mounted in spaced relation at opposite sides of the gate, means coöoperating between the 65 levers and drum whereby swinging of either lever will swing the gate if the latch is released, and means carried by the levers and operable to release the latch, said means including sleeves encircling the levers and 70 free for limited turning movement thereabout, drums mounted upon the sleeves, and flexible elements connected to the latch lever and operatively connected to the drums.

3. A gate construction including gate 75 posts, a gate having a hinge stile whereby it is swingingly supported by one of the posts, a latch for securing the gate, normally against movement, a latch lever carried by the gate and operatively connected to the 80 latch, a drum fixed to the hinge stile whereby turning of the drum will cause swinging of the gate, hand levers pivotally supported at opposite sides of the hinged end of the gate and in spaced relation thereto, a drag 85 link pivotally connected at its ends to corresponding ends of the hand levers and having its intermediate portion slidably supported by the post by which the gate is supported, a flexible element passed about the 90 drum and connected at its ends to opposite end portions of the link whereby reciprocation of the link through swinging of a hand lever will swing the gate, and means carried by the hand levers for operating the latch 95 lever.

4. A gate construction including gate 100 posts, a gate having a hinge stile whereby it is swingingly supported by one of the posts, a latch carried by the gate, a keeper 105 carried by the other post and engageable by the latch, a latch lever carried by the gate and operatively connected to the latch, a drum fixed to the hinge stile whereby turning of the drum will cause swinging of the 110 gate, hand levers pivotally supported at opposite sides of the hinged end of the gate and in spaced relation thereto, a drag link pivotally connected to corresponding ends of the hand levers, a flexible element passed about the drum and connected at its ends to opposite end portions of the link whereby reciprocation of the link through swinging of the levers will swing the gate, and means carried by the levers for operating the 115 latch lever, said means including sleeves mounted for limited turning movement about the levers, drums fixed to the sleeves, and flexible elements connected at their ends to the sleeve drums and at their other 120 ends to the latch lever.

In testimony whereof I affix my signature.

CHARLES H. SIMPSON. [L.S.]
